UNITED STATES PATENT OFFICE

137,279

DESIGN FOR AN AIRPLANE

Robert W. Ayer, Moorestown, N. J., and Thomas Knox, Bristol, and George S. Thompson, Morrisville, Pa., and Carl de Ganahl, Trenton, N. J., assignors, by mesne assignments, to Reconstruction Finance Corporation

Application April 30, 1943, Serial No. 110,084

Term of patent 14 years

To all whom it may concern:

Be it known that we, Robert W. Ayer, a citizen of the United States, residing at Moorestown, in the county of Burlington and State of New Jersey; Thomas Knox, a citizen of the United States, residing at Bristol, in the county of Bucks and State of Pennsylvania; George S. Thompson, a citizen of the United States, residing at Wakefield Township, Morrisville, in the county of Bucks and State of Pennsylvania, and Carl de Ganahl, a citizen of the United States, residing at Trenton, in the county of Mercer and State of New Jersey, have invented a new, original and ornamental Design for an Airplane, of which the following is a specification, reference being had to the accompanying drawings, forming a part thereof.

Fig. 1 is a top plan view of an airplane showing our new design;

Fig. 2 is a front elevational view with the landing gear in extended position; and

Fig. 3 is a side elevational view thereof with the landing gear shown in extended position.

We claim:

The ornamental design for an airplane, as shown.

ROBERT W. AYER.
THOMAS KNOX.
GEORGE S. THOMPSON.
CARL DE GANAH.
